UPHOLSTERY FASTENING MEANS FOR
FURNITUREWister Pervis Bott, Monroe, La., assignor to
Porter Earl Dozier, Shreveport, La.

Application March 22, 1948, Serial No. 16,278

1 Claim. (Cl. 155—184)

1

This invention relates to upholstered furniture. At the present time in the upholstering of furniture, after the padding has been applied, the covering is secured over the padding, and the covering is tacked to the frame. In the event the covering becomes pulled or wrinkled, the tacks must be removed, and where a complete new covering is to be applied, the original tacks must be removed and the new covering tacked on. It is, therefore, an object of this invention to provide an improved means for securing the covering over the padding and frame so that the covering may be tightly applied without tacks. This procedure will make it a simple matter to reupholster the furniture.

Another object of this invention is to provide as a new article of manufacture, an upholstering fastening means in the form of an elongated toothed strip which is adapted to be secured to the frame in such a manner that the covering will be tightly held in place, the teeth of the strip being so mounted on the frame that they will not catch clothing.

A further object of this invention is to provide an improved frame which can be readily taken apart for recovering or other purposes.

A further object of this invention is to provide detachable side or end panels and a back panel which is formed of a flat sheet of material having a thin padding and a covering over the padding, the sheet including toothed covering securing means for detachably holding the covering in place, and the frame and sheet having complementary fastening means for detachably holding the panel on the frame.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a perspective view of a furniture frame embodying this invention.

Figure 1a is a detailed side elevation of one of the removable panels.

Figure 2 is an enlarged fragmentary sectional view taken substantially on the line 2—2 of Figure 1 showing the padding and covering in position.

Figure 3 is a fragmentary side elevation of one of the covering securing strips.

2

Figure 4 is a sectional view taken on the line 4—4 of Figure 3.

Figure 5 is a fragmentary inner side elevation of a corner of one of the removable panels.

Figure 6 is an enlarged fragmentary sectional view similar to Figure 2.

Figure 7 is a fragmentary sectional view taken on the line 7—7 of Figure 5.

Figure 8 is a fragmentary inner side elevation of a modified form of this invention.

Figure 8a is a sectional view taken on the line 8a—8a of Figure 8.

Figure 9 is a fragmentary sectional view of another modification of this invention.

Referring to the drawings and first to Figure 1, the numeral 10 designates generally a side frame structure having mounted therein a seat frame structure 11 and a back frame structure 12 is secured to the rear of the side frame structures or members 10. The side members 10 are formed of front and rear legs 13 and 14, respectively, connected together by upper and lower rails 15 and 16. An intermediate rail or bar 17 is connected between the legs 13 and 14 and a second intermediate rail 18 is connected between the rail 17 and the lower rail 16. The seat frame 11 comprises a front bar or rail 19, a pair of side bars or rails 20 and a rear bar or rail 21.

The seat frame 11 is secured between the side frames 10 by means of a pair of bolts 22 on which wing nuts 23 are threaded. In this manner the seat frame 11 is adapted to hold the side frames 10 in upright position and the seat and side frames can be readily detached from each other.

The back frame 12 includes upright side members 24 and upper and lower connecting bars or rails 25 and 26, respectively. The back frame 12 is secured between the legs 14 of the side frame 10 by means of pairs of bolts 27 on which wing nuts 28 are threaded. The side, seat and back frames are adapted to be covered with a conventional padding and conventional spring means may also be applied to at least the seat frame. In order to provide an improved means

whereby the outer covering for each frame member may be easily and quickly applied and removed for recovering, I have provided a toothed covering securing strip, generally designated as 29. The strip 29 is formed of an elongated metal strip having a body or base 30 formed with openings 31 through which nails or tacks are adapted to be extended for securing the body strip 30 about the furniture frame.

The body 30 has extending from one lengthwise edge thereof an obtusely disposed extension

32 and a plurality of lengthwise spaced teeth 33 extend from the extension 32. These teeth 33 are preferably spaced apart from each other thereby providing a straight-edged portion 34 which is adapted to be engaged by the covering. The extension 32 and the teeth 33 are bent outwardly from the body 30 so that the covering securing strip may be secured to any selected portion of the furniture frame either along one edge thereof with the teeth projecting from such edge or at a point between adjacent edges of the frame elements.

As shown in Figures 2 and 6, one covering securing member 29 is secured to the outer side of a rail 15 of a side frame, after the inner padding covering 35 has been secured to the frame. The outer covering 36 is then engaged with the teeth of the securing member 29 and tightly pulled in place. As shown in Figure 2, a second outer covering holding member 29 is disposed on the lower rail 18 and has the teeth thereof projecting downwardly. The outer side of each side frame 10 is covered by means of a padded panel, generally designated as 31. The panel 31 includes a flat sheet 38 which may be formed of a sheet of metal having returned marginal edges 39 within which the covering holding members 29 are adapted to be engaged.

A thin padding 40 is interposed between the outer covering 41 and the outer side of the sheet 38 and the outer covering 41 is extended over the marginal edges of the sheet 38 and engaged with the teeth of the securing members 29. At the corners of the sheet 38 a cornerpiece 42 is inserted under the returned portions of the sheet 38 and the cornerpiece 42 is formed with teeth 43 similar to the teeth 33. In this manner a continuous line of teeth is formed about the entire marginal portion of the panel so that the outer covering 41 can be tightly and evenly secured about the sheet 38.

The panel 31 is adapted to be detachably secured to the side frame 10 by means of complementary snap fastening elements 44 and 45. The fastening element 44 is preferably the female element and is secured to the inner side of sheet 38 whereas the fastening element 45 is the male element and includes a screw 43 threaded into an adjacent portion of the side frame. It will be understood that a padded panel similar to panel 38 will be disposed on the outer side of each side frame and also on the back of the back frame. A similar panel may also be engaged along the front portion of the seat frame.

Referring now to Figures 8 and 8a, there is disclosed a modified form of panel construction wherein the sheet 47 is formed with a returned marginal portion 48 and the covering holding teeth 49 are formed integral with the returned portion 48. The teeth 49 are bent outwardly from the adjacent face of the sheet 47 so that the covering can be readily engaged with the teeth.

Referring now to Figure 9, there is disclosed another modification of this invention, wherein the panel sheet 50 is formed of plywood. In this instance, the covering holding member 29a is nailed or otherwise secured as indicated at 51 to one side of the panel sheet 50.

In the use of this invention the furniture frame is formed of detachably connected together side, seat and back frame members as herein described. Before the frame members are connected together they are padded and provided with the conventional spring structure and after the padding the inner covering for the padding has been applied, the outer covering is tightly stretched over the inner padding covering. The securing strips 29 are nailed or otherwise secured to the frames at selected and suitable points about the frame so that the outer covering may be tightly held. With a covering holding means as hereinbefore described in the event the outer covering should be wrinkled or became twisted, the outer covering may be easily and quickly applied correctly by pulling the covering from certain teeth of the holding strips and stretching the covering in the correct manner. The outer panels 31 are then snapped onto the male fastening members 45 which are secured to the furniture frame. With a covering fastening means as hereinbefore described, it is a very simple matter to reupholster or recover the furniture, particularly where the furniture frame is bolted together after the manner shown in Figure 1.

What I claim is:

Means for securing the outer covering to an upholstered chair formed of a plurality of panel members including plates having reverted marginal edges cut away at the corners comprising a plurality of straight sheet metal strips arranged to conform to the configuration of the margin of each panel, fastening means for securing said strips to the panel seated in the reverted marginal edges of said plates, corner strips having their end portions underlying the adjacent ends of adjacent straight strips and a plurality of teeth extending from the inner edge of each straight and corner strip and inclined at an acute angle toward and outwardly of the plane of its adjacent panel.

WISTER PERVIS BOTT.
